UNITED STATES PATENT OFFICE.

LEO S. ROBINSON, OF ALAMEDA, CALIFORNIA.

DENTAL TOOL.

No. 876,842.

Specification of Letters Patent.

Patented Jan. 14, 1908.

Application filed July 18, 1906. Serial No. 326,692.

To all whom it may concern:

Be it known that I, LEO S. ROBINSON, citizen of the United States, residing at Alameda, in the county of Alameda and State of California, have invented new and useful Improvements in Dental Tools, of which the following is a specification.

My invention relates to rotary abrading, cleaning and polishing tools used in the practice of dentistry, and pertains especially to the combination by novel means in a unified structure of a dental disk, or grinding and polishing annulus, and a hollow mandrel.

My invention consists of the parts and the construction and combination of parts as hereinafter more fully described and claimed, having reference to the accompanying drawings, in which—

Figure 1 is an end view of a dental tool embodying my invention. Fig. 2 is a longitudinal sectional view of the same. Figs. 3, 4 and 5 are similar sectional views of modified construction to be hereinafter described.

In the preferred form of my invention, with particular reference to bristle brushes, and shown in Figs. 1 to 3 inclusive

A represents a tubular shank, stem or mandrel of ordinary metal tubing, of appropriate size and length. This tube may be seamed or seamless, so long as it is expansible; and for dental purposes is usually about 3/32" O. D. (outside diameter).

2 is a short sleeve fitting over one end of tube A, and having a suitable integral annular flange 3, made of suitable shape to form a seat for one side of the brush.

5 is a washer corresponding in shape to the flange or head 3 and adapted to support the opposite side of the bristle disk 4.

6 is a common wire nail adapted to be passed through washer 5 and through the center of the bristles and to be forced or driven into the tube A to expand the latter against the surrounding sleeve 2 and hold the parts fixedly together.

The main feature of this invention is the use of a hollow expansible stem or mandrel having a bore of relatively smaller diameter than that of the nail, whereby the latter will act expansively when driven home to hold the sleeve to the mandrel, and to clamp the disk between the parts 3—5. These nails may represent the ordinary wire or other nails whose well known barbs, not shown, operate to bite into the tube and prevent the nail from working loose.

The brush 4 is preferably made by taking a bundle of bristles b and binding them about the middle as at b', The nail 6 having the washer 5 in position, is then passed lengthwise through the center of this bundle, and the point of the nail is inserted into the end of the tube A. When the nail is driven into tube A to expand the latter, the parts 3—5 act to spread the two ends of the bundle umbrella fashion, and to fold them so that when the nail is driven up to the head, the complete brush 4 will be formed, all of the parts of the device being rigidly and permanently connected.

In Fig. 4 I show a modification of the invention in which the same principle of a hollow shank A' and nail 6' is used, but the cup 3' is separate from the sleeve 2'. The washers and cups may be of any shape or size according to the description of brush desired.

In Fig. 5 is shown a further modification wherein the washer is omitted and the head 5^a of the nail 6^a bears directly against the bristles.

In all cases the outer sleeve 2—2' &c., acts as a reinforce to the end of the tubular mandrel, and the several parts of the brush are held fixedly together in a unitary structure by the expansive action of the nail. In all cases the parts are assembled and bound together by a single operation, that of simply driving the nail into the mandrel.

While I have spoken of "disk like" brushes in this specification it is manifest that the same principle covers the construction of cup-shaped brushes as in Fig. 4. In fact by "dental disk" or "dental annulus", I mean any shape of rotary brush or grinder, polisher or the like.

Having thus described my invention, what I claim and desire to secure by Letters Patent, is—

1. In a dental tool, the combination of a tubular expansive mandrel, a sleeve fitting the end of the mandrel, a dental disk, a flange and washer between which the disk is held, and a nail passed through the washer and disk and forced into the tube to expand the latter against the sleeve and hold the disk in fixed position between said flange and washer.

2. A rotary dental tool comprising a hollow stem, a flanged sleeve fitting an end of the stem, a nail driven into the end of the stem embraced by said sleeve to expand the stem against the sleeve, and a dental annulus

clamped between a member carried by the outer end of the nail and the flange on the adjacent end of the sleeve.

3. A brush comprising a hollow - expandable stem, a sleeve to embrace an end of the stem, a nail of larger diameter than the bore of the stem driven into the end of the stem embraced by the sleeve, opposed co-acting members surrounding the nail, said members 10 consisting of a flange on the sleeve and a washer carried by the nail, and a brush comprising a bundle of fibers bound around their middle with said nail passed lengthwise through the bundle and driven into the stem 15 to fold the bristles and spread them radially between said flange and washer and unite the bristles, sleeve, washer and stem in a rigid unitary structure.

4. A rotary dental tool comprising a hollow stem, a sleeve fitting an end of said stem, 20 a flange at the end of said sleeve, a brush comprising a bundle of fibers bound around their middle, a nail of larger diameter than the bore of said stem extending through the center of the bundle of fibers and into the end 25 of the portions of the stem embraced by said sleeve, said nail being provided with means for clamping the bundle of fibers against said flange.

In testimony whereof I have hereunto set 30 my hand in presence of two subscribing witnesses.

LEO S. ROBINSON.
